ATTORNEY

UNITED STATES PATENT OFFICE.

JOHN McE. AMES, OF NEW YORK, N. Y., ASSIGNOR TO AMERICAN CAR AND FOUNDRY COMPANY, OF ST. LOUIS, MISSOURI, A CORPORATION OF NEW JERSEY.

CARLINE.

1,097,962.

Specification of Letters Patent. Patented May 26, 1914.

Application filed July 3, 1911. Serial No. 636,689.

To all whom it may concern:

Be it known that I, JOHN McE. AMES, residing at New York, N. Y., and being a citizen of the United States, have invented 5 certain new and useful Improvements in Carlines, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is an elevational view of the improved carline secured 20 in position upon the side plates of a car, said side plates being shown in section. Fig. 2 is a plan view of the carline. Figs. 3 and 4 are transverse sectional views taken respectively on lines 3—3 and 4—4 of Fig. 25 2 looking in the direction indicated by the arrows. Fig. 5 is a fragmentary end view of a modified form of carline secured in position upon one side plate, and Fig. 6 is a further modification illustrating the carline of the other figures and provided with 30 a tension tie rod, or strap, which is riveted directly to the vertical portion of the carline and may be applied to the designs shown in the other figures.

Referring to the parts; F indicates the carline, generally speaking, which is preferably formed from a commercially rolled angle section such as is shown in the sectional view Fig. 4, wherein the vertical leg 35 H is longer than the horizontal leg G thereof and retains the fillet I incident to commercially rolled sections of metal. It is preferred that the carline shall be secured in position upon the side plates B—B' by 40 means of vertical and horizontal bolts S passing through flanges of the carline and through said side plates. As will be noted in the sectional view Fig. 3, the vertical flange H of the carline is bent inwardly be- 45 neath the horizontal flange G at 1 thereby

forming the end portions of the carline into relatively channel shape.

The top flange G is continued as shown in Figs. 1, 5 and 6 so as to overlap the side plates at 2 and continue downwardly on the 55 outer sides thereof as shown at 3 in the preferred construction. This flange 3 may continue downwardly as shown in Figs. 5 and 6 far enough to take the horizontal bolts S or it may terminate above said horizontal 60 bolts as shown in Fig. 1, as may be preferred. The bottom flange 1 is continued beyond the web H in the preferred construction and extends downwardly as shown at 1^a in Figs. 1 and 6, being perforated for 65 the passage therethrough of the horizontal bolt S, while in the modified construction shown in Fig. 5 this flange is bent upwardly at 1^b, extends over the side plate B and is provided with a perforation coincident with 70 the perforation in the top flange G for the passage of the vertical securing bolt S, while the horizontal securing bolt extends only through the depending flange 3 which forms an extension of the top web portion 75 G. To provide the depending flange referred to, the vertical flange H is cut away as best shown in Figs. 1 and 5, said vertical web portion terminating inside of, or between the side plates B—B'. Thus there is 80 provided a very strong, simple and economical carline which for all ordinary purposes, is sufficiently stiff for service conditions. To reinforce the carline thus provided, there is added thereto, when desired, the 85 tension tie rod 6 shown in Fig. 6, which tension tie rod is secured by rivets 7 to the vertical leg H of the carline, resting preferably upon the inturned flanges 1 thereof as best shown in Fig. 6.

Having described the invention, what is claimed as new is:—

1. In a carline, a member formed with channel shaped portions near its ends and a tension member secured to said channel shaped portions between its top and bottom flanges.
2. A carline comprising a cambered member with horizontal and vertical flanges with portions of the vertical flanges bent 100

inwardly to underlie portions of the horizontal flange and a tension member secured above said underlying portions.

3. In a carline, the combination of an integral member comprising an angle member at the center thereof formed with channel-shaped portions at each end thereof, and a tension member having its ends disposed

between the flanges of the channel portions of said member at each end thereof.

In witness whereof I have hereunto set my hand in the presence of two witnesses.

JOHN McE. AMES.
